UNITED STATES PATENT OFFICE.

HARRY A. DOUGLAS, OF BRONSON, MICHIGAN, ASSIGNOR TO DOUGLAS & RUDD MFG. CO.,
OF BRONSON, MICHIGAN, A CORPORATION OF MICHIGAN.

REFLECTING ELECTRIC LAMP.

1,261,783.

Specification of Letters Patent.

Patented Apr. 9, 1918.

Application filed February 19, 1917. Serial No. 149,664.

To all whom it may concern:

Be it known that I, HARRY A. DOUGLAS, a citizen of the United States, residing at Bronson, in the county of Branch and State of Michigan, have invented a certain new and useful Improvement in Reflecting Electric Lamps, of which the following is a full, clear, concise, and exact description.

My invention relates to connectors and 10 to reflecting lamps employing them. One object of the invention is to provide unitary means for switching the lamp into and out of circuit and effecting its focal adjustment, this part of the invention relating particularly to those lamps having casings and reflectors spaced apart from and in front of the casings.

The invention has for another of its objects a modification of a connector shell to 20 improve and facilitate the assembly thereof with a contact carrier or carriers. In carrying out this feature of the invention the bayonet slot in the shell is continued inwardly beyond a bayonet seat formed 25 therein to elongate such slot and thereby increase the length of the split in the shell that it effects. The inner end of this slot may have an additional bayonet seat to accommodate a second contact carrier. If this latter contact carrier is a switching plug the inner end of said slot has two seats for alternative engagement with the second contact carrier to enable such carrier to be placed in circuit opening and closing positions.

I will explain my invention more fully by reference to the accompanying drawings showing the preferred embodiment thereof and in which Figure 1 is a view in elevation, partially in section, of a reflecting electric lamp as it is preferably constructed in accordance with my invention; Fig. 2 is a view in elevation, partially in section, of portions of the structure shown in Fig. 1; Fig. 3 is a view on line 3-3 of Fig. 2; Fig. 4 is a view on line 4-4 of Fig. 3; Fig. 5 is a view on line 5-5 of Fig. 2; Fig. 6 is a perspective view showing the parts of the connector of my invention in 45 separated relation, the forward contact car-

rier, however, being omitted; Fig. 7 shows two parts of the lamp adjusting mechanism; Fig. 8 shows two more parts of the lamp adjusting mechanism, the part at the right hand being shown in the condition in which it appears before it is assembled; and Fig. 9 is a view on line 9-9 of Fig. 2.

Like parts are indicated by similar characters of reference throughout the different figures.

The concave reflector 1 is received in and is suitably coupled with the reflector carrying concave casing 2, space intervening between the rear portions of the reflector and casing. The reflector carries a rearwardly extending tubular holder or mounting 3 that projects rearwardly from the rear portion of the reflector into the space between the reflector and casing. A spring tongue 4 is integrally formed with a shell 5 that constitutes a holder for contact carriers, this spring tongue having ample clearance at its side margins to permit it freely to function. Some part of the tongue, such as the rear free end thereof, has a part 6 projecting therefrom which is narrower than the balance of the tongue and is slightly narrower than a slot 7 in the holder 3 whereby this portion may project into the slot to prevent the shell from turning with respect to the slot while at the same time the side margins of the tongue 4 are adapted to press against the side margins of the slot 7. The tongue thus presses upon a surface of the holder 3 and, where there is but one tongue, forces the shell toward the opposite side of the holder whereby the shell is held in engagement with the holder 3. The slot 7 is elongated so that the shell 5 may be moved forwardly and rearwardly in its holder 3 whereby in the structure illustrated the position of the lamp bulb 8 which is carried by the forward end of the shell in front of the reflector may be focally adjusted with respect to the reflector. The base 9 of the lamp bulb 8 constitutes the forward contact carrier and as the arrangement illustrated is a double pole arrangement this contact carrier 9 carries two rear contacts 10 and 11. The lamp base or contact carrier 9 is 100

provided with bayonet pins 12 engageable within bayonet seats 18 constituting parts of bayonet slots 14. By continuing the slot 14 beyond the seat 18, the shell is further 5 split to enable it to have more tight engagement with the contact carrier 9 which is snugly received in the shell. The rear contact carrying plug 15 within the space between the rear portions of the casing and 10 reflector is provided with terminal blocks 16 having binding screws 17 by which circuit wires may be secured to the terminal blocks. These terminal blocks are cylindrical and the forward ends thereof are tubular, springs 15 18 being included in the tubular portions of the terminal blocks and operating to press contacts 19 and 20 forwardly into engagement with the contacts 10 and 11, all of these contacts being within the casing. The 20 springs 18 and the contacts 19 and 20 thus not only serve to establish circuit for the lamp but also operate to hold the lamp base 9 in bayonet pin and slot connection with the shell 5.

25 The plug 15 is preferably rotatable within the rear end of the shell 5 in order that it may perform its switching function and when thus movably mounted it is desirably provided with bayonet pins 21 which are receivable in alternate bayonet seats 22, 23, the plug being desirably inserted from the front end of the shell with its pins passing along the bayonet slots 14 until they are in the zone that includes the transversely spaced apart 30 inner bayonet seats 22, 23 whereafter the base of the lamp bulb is inserted in the shell with its pins 12 placed in the bayonet seats 13. The end of the shell adjacent the plug is circumferentially continuous, it being unnecessary to slot this end of the shell to afford the pin and slot engagement between the rotatable contact carrier and the shell that defines the limits of rotation of the rotatable contact carrier. The springs 18 thus 40 not only serve to hold the bayonet pins 12 in the seats but also serve to hold the bayonet pins 21 in the seats to which they are adjusted.

45 It will be observed that the complementary switching contacts 10 and 19 are eccentric with respect to the shell as are also the complementary switching contacts 11 and 20 so that as the plug is turned these contacts are either brought into engagement or are separated according to the direction of movement of the switching plug 15. When the lamp is in open circuit the contacts 19 and 20 are pressed against the insulating portions of the lamp base that are adjacent the 50 contacts 10 and 11, the springs 18 continuing to press the contacts 19 and 20 forwardly to maintain the bayonet pins upon the switching plug and upon the lamp base in their respective bayonet seats. The shell and the parts within it are in front of the 65 casing 2 and in order that the switching plug 15 may be turned or otherwise moved with respect to the lamp base to cut the lamp in and out of circuit I employ a motion transmitting connection, preferably in the form 70 of a forwardly and rearwardly movable and rotatable switching rod or motion transmitting element 24, which is connected at its inner end with the switching plug (which is movable back and forth) and which rod is 75 extended rearwardly to be operable from the exterior of the casing.

A rotatable sleeve 26 has its rear end at the exterior of the casing, this rear end being reduced and knurled so that it may 80 readily be grasped to turn the sleeve. The bore of the sleeve is in threaded engagement with the rear end of the rod 24. The external part of head piece 25 constitutes an abutment and there is a second abutment 85 27 upon the interior of the casing, these two abutments being held in rigid relation with each other and in turning relation with the casing by means of tongue formations 28 that are passed through openings 29 in the 90 abutment 27 and which are turned over (as indicated in Fig. 2) to afford proper space between the abutments in which the surrounding portion of the part or handle continuation 21 of the casing may be received. 95 By this arrangement the rod turning head piece 25 is confined to a single plane of rotation, the parts thereof which have been termed abutments engaging the ends of the enlarged part of the sleeve 26 so that the 100 sleeve 26 is also confined to a single plane of rotation. By turning the sleeve the rod 24 may be moved back and forth to adjust the lamp bulb 8 with respect to the reflector 1. The head piece 25 may be turned with 105 respect to the sleeve 26 and in order that it may turn the rod 24 the abutment part 27 of the head piece carries a square tubular end 30 engaging the square end of the rod 24 that is shown most clearly in Fig. 7. The 110 corner portions of the square end of the rod 24 are threaded to engage the threads in the sleeve 26 but these threads are merely surrounded by the square tube 30 without having any engagement of their own with the 115 head piece, the engagement of the head piece with the rod being confined to the flat faces of the square end of the rod and the inner flat faces of the square tube 30. Thus the rod 24 may be merely moved in and out by turning the 120 sleeve 26 alone or may be merely turned by turning the head piece 25 alone respectively to adjust the lamp with respect to the reflector or to switch the lamp in and out of circuit.

125 While I have herein shown and particularly described the preferred embodiment of my invention I do not wish to be limited to

the precise details of construction shown as changes may readily be made without departing from the spirit of my invention, but having thus described my invention I claim 5 as new and desire to secure by Letters Patent the following:—

1. In a reflecting electric lamp, the combination with a reflector carrying casing; of an electric lamp bulb; a shell carrying the lamp bulb at its front end; a contact carrying plug within the casing and coupled with the shell for supplying current to the lamp and mounted to turn with respect to the shell to cut the lamp in and out of circuit, there being engageable eccentrically located switching contacts in the lamp circuit, one upon the plug; a motion transmitting rod extending from the plug and operable from the exterior of the casing to turn said plug; and a head piece for the rod and engaged with the casing to confine it to a single plane of rotation.

2. In a reflecting electric lamp, the combination with a casing; of a reflector in front 25 of the casing, space intervening between the rear portions of the casing and reflector; an electric lamp bulb; a shell carrying the lamp bulb at its front and movable forwardly and rearwardly to effect focal adjustment of 30 the bulb; a contact carrying plug within the space between the rear portions of the reflector and the casing and coupled with the shell to be movable forwardly and rearwardly therewith in the focal adjustment of 35 the bulb and serving to supply current to the lamp, the plug also being mounted to turn with respect to the shell to cut the lamp in and out of circuit, there being engageable and separable switching contacts in the 40 lamp circuit, one upon the plug; and a forwardly and rearwardly movable and rotatable motion transmitting element connected with and extending rearwardly from the plug and operable from the exterior of the 45 casing to turn said plug to switch the lamp into or out of circuit and to move the plug in or out to move the shell and thereby effect focal adjustment of the bulb.

3. In a reflecting electric lamp, the combination with a casing; of a reflector in front 50 of the casing, space intervening between the rear portions of the casing and reflector; an electric lamp bulb; a shell carrying the lamp bulb at its front and movable forwardly and rearwardly to effect focal 55 adjustment of the bulb; a contact carrying plug within the space between the rear portions of the reflector and the casing and coupled with the shell to be movable forwardly and rearwardly therewith in the focal adjustment of the bulb and serving to supply current to the lamp, the plug also being mounted to turn with respect to the shell to cut the lamp in and out of circuit,

there being engageable and separable switching contacts in the lamp circuit, one upon the plug; a forwardly and rearwardly movable and rotatable motion transmitting rod connected with and extending rearwardly from the plug and operable from the exterior of the casing to turn said plug to switch the lamp into or out of circuit and to move the plug in or out to move the shell and thereby effect focal adjustment of the bulb; and a head piece for the rod whereby the rod may be turned and with respect to which the rod is longitudinally movable, said head piece being confined to substantially a single plane of rotation by the casing.

4. A connector including a contact carrier having a bayonet pin; a shell receiving the contact carrier, said shell having a slot extending from one end of the shell toward the other and formed with a seat at an intermediate portion in which said bayonet pin is receivable in assembling the shell and carrier, the inner end of said slot being formed to furnish two additional bayonet seats; and a rotatable switching contact carrying plug within the shell having a bayonet pin alternately receivable in said latter bayonet seats and forming with the first contact carrier a switch for opening and closing circuit.

5. A connector including a contact carrier having a bayonet pin; a shell receiving the contact carrier, said shell having a slot extending from one end of the shell toward the other and formed with a seat at an intermediate portion in which said bayonet pin is receivable in assembling the shell and carrier, the inner end of said slot being formed to furnish an additional bayonet seat; and a contact carrying plug within the shell having a bayonet pin receivable in said latter bayonet seat.

6. In a reflecting electric lamp, the combination with a reflector carrying casing; of an electric lamp bulb; a shell carrying the lamp bulb at its front end; switching contacts within the casing for cutting the lamp in and out of circuit; a plug within the casing and coupled with the shell and carrying one of said contacts and movable with respect to the shell; and means operable from the exterior of the casing for effective relative motion between the plug and shell to cut the lamp in and out of circuit and for effecting movement of the shell and the lamp bulb in and out to adjust the lamp bulb with respect to the reflector.

7. In a reflecting electric lamp, the combination with a reflector carrying casing; of an electric lamp bulb; a shell carrying the lamp bulb at its front end; engageable eccentrically disposed switching contacts within the casing for cutting the lamp in and

1,261,783

out of circuit; a plug within the casing and mounted to turn in the shell and coupled therewith and carrying one of said contacts; and means operable from the exterior of the casing for turning the plug to cut the lamp in and out of circuit and for effecting movement of the shell and the lamp bulb in and

out to adjust the lamp bulb with respect to the reflector.

In witness whereof, I hereunto subscribe my name this 24th day of January A. D., 1917.

HARRY A. DOUGLAS.
